UNITED STATES PATENT OFFICE

2,537,331

KERF CUTTER

William C. Cassell, Williamson, W. Va.

Application March 21, 1947, Serial No. 736,335

2 Claims. (Cl. 262—30)

1

My invention relates to an improvement in mining machinery, particularly to a means and method for controlling the front end of a cutter bar.

It is a principal object of my invention to provide a means and method for controlling the upward and downward movement of the front end of the cutter bar of a coal cutting machine while said end is inserted in the cut made in a coal pocket.

It is an important object of my invention to combine hydraulic jacks with the cutter bar of a standard coal cutting machine in such manner that the said cutter bar may be adjusted to cut nearer the bottom of the coal pocket than is possible in any known coal-cutting machine, and to raise the said cutter bar if rock is encountered.

It is a further object of my invention to provide such means and method which is quickly adjustable to any desired cutting position so that the horizontal kerfs cut in the coal face will be neither too far from the rock bottom or too high in the coal bank.

It is a still further object to provide such means and method as will permit such control as to cut out a larger percentage of impurities with less coal waste.

It is another object to provide such means as will be simple and efficient in its operation, and which will greatly reduce wear and tear on the cutting bits since rock ledges may be avoided.

Other objects and advantages of the invention will become apparent during the course of the following specification and accompanying drawings, forming part of the specification, wherein like numerals are used to designate like parts throughout.

In the drawings:

Figure 1 is a side elevation of a kerf cutter embodying my invention with the cutter bar inserted in a kerf cut in a coal pocket, and illustrating the application of my fluid system on the machine.

Figure 2 is a vertical section through the "up" jack cylinder.

Figure 3 is a transverse section through the same, taken substantially on the line 3—3 of Figure 2, and

Figure 4 is a diagrammatic view of the fluid system, a fragment of the front end of the cutter bar and a few of the kerf cutting bits being shown.

Referring now in detail to the drawings, the numeral 10 refers generally to a standard kerf cutting machine of the bottom cut type, pro-

2

vided with the usual means for controlling the outwardly extending cutter bar 11 mounted on the said machine for pivotal up and down movement. A plurality of cutting bits 12 are mounted on an endless chain (not shown), and adapted to rotate about the margin of the said cutter bar to cut the horizontal kerf in the coal pocket. Since the machine 10 is well known in the art, and forms no part of my invention other than 10 will be hereinafter described, no further description need be given.

Referring now to the fluid system of my invention, the numeral 13 designates a fluid compression tank containing a fluid, preferably oil, 15 supported on the body of the machine 10. The tank is provided with an internal reciprocal piston 14 adapted to pump the fluid under pressure by means of a pivoted handle 15 through suitable ports into a conduit 16 leading to a pair of 20 standard manually operated rotary valves 17 and 18, each said valve having a control handle 19 and 20, respectively. The said tank 13 is also provided with means to receive fluid from a return conduit 21. Since any standard compression tank and three way valve may be used, these elements are not further described.

The numeral 22 designates a spring-loaded cylindrical hydraulic jack suitably mounted in the cutter bar 11 adjacent the front end thereof. 30 It comprises a fluid-tight cylinder comprising a bottom portion 23 having a port 24 through which fluid under pressure may be received by means of a conduit 25 connected to the source of fluid through the valve 17 and a threadedly 35 connected top portion 26 provided with an integrally formed dependent annular flange 27 arranged for up and down transverse sliding movement along the inner periphery of bottom portion 23 providing a stop for the heads 28 of a piston 29 adapted to reciprocate within said cylinder under pressure of the fluid supplied through the conduit 25 under control of the valve 17, the thrust of the said piston 29 being adjustable for a desired amount of raising by 40 means of the threaded connection 30 between the bottom portion 23 and the top portion 26. A helical compression spring 31 is suitably connected to the bottom of the lower portion 23, as at 32, and at the top of an apertured recess 45 33 in the piston 29 and head 28, as at 34, to return the said piston to its normal position quickly upon reduction of the pressure within the said cylinder, the said spring tensioning with the upward movement of the piston 29. The said 50 jack will force the cutter bar downward if cut-

ting too high in the coal pocket by pressure of the piston 29 against the top of the kerf when fluid is admitted into the cylinder through the manually controlled valve 17.

The numeral 35 designates a jack of identical construction with the jack 22, except that the spring 31 and its connections to the bottom of the cylinder and within an aperture are omitted. Since the piston 36 of valve 35 depends downward to impinge upon the bottom of the kerf, such a spring is not needed. The said piston being pushed back into the cylinder 37 by the pressure of the bottom of the kerf when inside fluid pressure is relieved. The jack 35 is supplied with hydraulic fluid through the conduit 38 and said pressure is controlled by the valve 18.

It is to be understood that the jacks 22 and 35 are mounted in the cutter bar 11 so that the outer surfaces of the respective pistons 29 and 36 are normally substantially level with the respective top and bottom surfaces of the said bar to provide no obstruction to the normal use of the bar.

While I have described my invention in connection with a bottom cutting type of kerf machine, it is to be understood that it may also be used with a track or mobile kerf cutter. It is to be further understood that various changes in the shape and arrangement of the parts, or substitution of materials and equivalents may be made without departing from the spirit of the invention within the scope of the subjoined claims.

The operation of my fluid system is very simple. If the machine is cutting in rock, by operating the compressor tank 13 fluid under pressure is forced into the jack 35 and the front end of the cutter 11 is forced upward. If the cut is too high, fluid is forced into the jack 22 and the

cutter is forced downward. Control is maintained through the respective valves 18 and 17. Relieving the pressure in the respective jacks causes the jacks to return to their normal positions as heretofore described.

Having thus disclosed my invention, I claim:

1. A kerf cutting machine comprising a frame adapted to slide along its bottom wall and a relatively narrow cutter bar extending from the frame and rigidly connected thereto, an endless cutter chain carried by the cutter bar, a source of fluid pressure mounted on the frame, means for controlling the direction of flow of the fluid pressure, hydraulic jacks connected to the source of fluid pressure and mounted within the cutter bar adjacent the free end thereof and in alignment with the longitudinal axis of the cutter bar, the jacks being extendable in opposite directions to depress and raise the free end of the cutter bar when actuated by the fluid pressure.

2. A kerf cutting machine as set forth in claim 1, wherein a portion of the cylinder is adjustable to vary the throw of the jack and the amount of vertical movement of the cutter bar.

WILLIAM C. CASSELL.
